UNITED STATES PATENT OFFICE.

NELSON I. TEFFT AND DEWEY D. TEFFT, OF PERRY, NEW YORK.

CLOTH-CUTTING MACHINE.

No. 805,104.

Specification of Letters Patent.

Patented Nov. 21, 1905.

Application filed March 11, 1905. Serial No. 249,673.

To all whom it may concern:

Be it known that we, NELSON I. TEFFT and DEWEY D. TEFFT, residing at Perry, in the county of Wyoming and State of New York, 5 have invented a new and Improved Cloth-Cutting Machine, of which the following is a specification.

Our invention seeks to provide an improved means for cutting cloth in predetermined 10 lengths from a roll or bolt in a convenient, quick, and accurate manner, and by which a large quantity of layers of cloth can be cut at one time and the said cloth cut in uniform lengths by measuring the cloth lengths on the 15 cuttings previously made, and in which the cloth pieces can be progressively built up in a column or mass in uniform layers and the cutting means readily adjusted to suit the differential heights at which the different layers 20 of cloth are held to be cut.

With the above and other objects in view our invention comprehends generally a suitable supporting-table, over which the cloth to be cut into lengths is drawn, a shearing 25 means vertically movable above the table and disposed transversely thereof, mechanism for elevating the said shearing means to bring the cutting members in proper position to sever the cloth at different horizontal planes with 30 respect to the bed of the table, and a second means for releasing the shearing-devices-elevating mechanism, whereby to allow the said shearing devices to drop back to their initial or lowermost position by gravity.

35 In its more complete nature our invention embodies a suitable transversely-slotted table, a cloth-holder mounted thereon, a frame vertically adjustable through the slot in the table, a fixedly-held cutter-blade and a movable cutter-blade mounted on the said frame, a foot-operated rack-and-pawl mechanism for actuating the said frame and a means for moving said rack-and-pawl mechanism out of an operative engagement with the vertically- 40 movable cutter-carrying frame.

45 In its more subordinate features our invention consists in certain details of construction and peculiar combination of parts, all of which will be hereinafter fully explained, and specifically pointed out in the appended claims and illustrated in the accompanying drawings, in which—

Figure 1 is a perspective view of our improved construction of cloth-cutting machine. 55 Fig. 2 is a transverse section thereof, taken on the line 2 2 of Fig. 3. Fig. 3 is a longitudi-

nal section of the same on the line 3 3 of Fig. 2. Fig. 4 is a perspective view of the fixed and movable cutter members and the frame on which they are mounted. Fig. 5 is a detail cross-section taken through the hinged end of the movable cutter. Fig. 6 is a horizontal section of one side of the machine, taken on the line 6 6 of Fig. 3.

In the practical application of our invention 65 the same comprises a suitable supporting means in the nature of a table-bed A, mounted on the four corner-legs a and including a forwardly-extending section a', separated from the main table top or bed, whereby to form a 70 cross-slot a², the purpose of which will presently appear, and held in the same horizontal plane with the main table-bed by the brackets a³ on the front legs a and a supplemental leg a⁴, and upon the forward end of the said table-section a is mounted a bracket a⁵, having 75 bearings to receive the spindles b of the roller upon which the cloth is wound, as clearly shown in Figs. 1 and 3.

C designates the cutter-frame formed in a 80 substantial L shape, which comprises a cross member c and a pair of bars c' c', pendently secured to the opposite ends of the cross member c and which have their inner faces provided with rack bars or surfaces c² c³, arranged to coöperate with rack-actuating devices presently fully explained. The pendent bars c' c' are held to slide vertically in grooves 1^a 1^a, formed in the front legs a a, and the frame C is movable up through the 85 slot a² in the table-bed, whereby the upper end or cross member c can be elevated above the table-bed to the distances desired to suit the thickness of the cloth pieces to be cut or the heights at which the cloth may be held in 90 position to be secured.

On the upper or cross member c is fixedly held, but adjustably secured, the stationary cutter-blade D, having the usual shear-edge construction and with which coöperates the 100 movable or severing blade D', which is adjustably mounted on a cutter-head bed D², of a length equal that of the cross member c of the frame C, having a handhold d² at the outer end and having its inner end hinged in a 105 bifurcated bracket E, mounted on one end of the cross-bar c, and which has a pair of opposing bearing-lugs e e, that engage corresponding bearing-sockets in the inner end of the head-bar D² to provide for taking up 110 wear and effecting a firm pivotal bearing for the cutter-head D², and to normally hold the

cutter D and its carrying-head D' normally to an elevated position to permit of freely drawing the cloth between the opposing cutters the inner or pivotal end of the head D' 5 has a counterbalance-weight D³, which serves to swing and hold the upper blade and the member D' to their elevated position, as shown in the drawings.

F designates a ratchet-actuating shaft 10 mounted transversely of the machine adjacent the cutter-carrying frame and supported in an adjustable frame composed of the oppositely-disposed upper and lower horizontal beams H, the ends of which are slidably held 15 in bearings n n on the front and rear legs a a of the main framing, as clearly shown in Figs. 1 and 6, and connected with each other near the rear end by the cross-bar h'. The cross-bar h' serves to engage the lever N, as shown. 20 N designates a lever-arm hinged at its lower end to a cross member a⁶ of the main frame to swing lengthwise of the frame and pivotally connected at the upper end to a hand-lever I, located under the table-top, pivoted 25 at one end to the said table-top, as at i, and having its free end extended beyond the front edge of the table to form a handle i².

The shaft F, which is journaled in the lower set of bars H H, carries at each end a pinion 30 J J, adapted to mesh with the rack members of the frame C, and it also at one end has fixedly connected therewith a ratchet-disk K, with which coacts a pawl l on a lever L, loosely mounted on the shaft F, pulled back 35 to its normal position by a coiled spring M, secured to the under side of the table.

T indicates a foot-lever, which connects with the outer end of the lever L, and G designates a segment secured to the frame H, 40 which has a series of apertures with which adjustably engages a stop-pin g to limit the down thrust of the lever L.

Q designates buffer-springs in the lower end of the grooves in which the rack members of the frame C slide for taking up the shock when the frame C drops by gravity. 45

From the foregoing, taken in connection with the drawings, it is believed the manner in which our invention is capable of being 50 operated and its advantages will be apparent to those skilled in the art to which it appertains.

By referring more particularly to Fig. 1 it will be noticed the cloth as it is unrolled is 55 carried over the slot in the table and back on the table to the distance desired, and when thus set the operator by pulling down the upper or hinged cutter causes the cloth to be quickly severed the desired length. Should 60 it be desired to cut a number of layers of cloth at one time, that is accomplished by folding the cloth between the knives and pulling down the upper knife as before. When it is desired to cut the cloth into a number of 65 pieces of the same length and to stack the

same, after the first length has been cut the operator measures the succeeding lengths by the length first cut, and as the different pieces form a column the operator successively raises the frame C with the cutters to bring the cutting edges of the two shearing-blades in the varying horizontal planes of the cloth to be severed by pressing the foot-lever and actuating the pawl-and-ratchet devices to turn the shaft F, and thereby through its pinions 70 and the racks on the frame C elevate the said frame C. To bring the frame down, the operator grasps the lever L, moves it in the direction indicated by the arrow 10 on Fig. 1, which pulls the frame H in the direction indicated by the arrow 110 on Fig. 3, and thus disengages the pawl-and-ratchet mechanism from the racks and frame C. To bring the frame H and the lever L back to their normal position to again engage the racks in 80 frame C, spiral springs h⁵ are located in sockets on the inner edges n of the rear legs a, as clearly shown in Figs. 3 and 6.

Our invention by reason of its simple arrangement of parts can be conveniently operated by unskilled labor and serves to cut the cloth properly in an expeditious manner, especially for stacking the severed pieces of uniform lengths without the additional handling after the cloth has been drawn out to the 90 lengths desired. Changes in the details of construction and modification thereof may be made without departing from the general principle of our invention and the scope of 95 the appended claims.

Having thus described our invention, what we claim, and desire to secure by Letters Patent, is—

1. In a cutting-machine of the character described, a cutting mechanism composed of a lower stationary knife and an upper movable knife, a support for said knives having vertical movement, and adapted to automatically lower, and a means for successively elevating the frame and holding it to its vertically-adjusted positions, as set forth. 105

2. In a cutting-machine of the character described, a table, a cutting mechanism including a pair of shearing-knives, disposed transversely of the table, a ratchet-and-pawl mechanism for elevating said cutting mechanism as a whole, with respect to the table, said ratchet-and-pawl mechanism being adjustably mounted whereby to become disengaged from the cutting mechanism when shifted, substantially 115 as shown and described.

3. The combination with the table and the cutter-carrying frame disposed transversely of the table and having vertical movement with respect to the table, said frame including a 125 pair of pendent rack-bars; of the horizontally-movable ratchet-and-pawl mechanism mounted at one end thereof to coact with the aforesaid pendent rack-bars, a foot-operated lever for actuating the ratchet-and-pawl devices, 130

means for automatically shifting the horizontally-movable frame in one direction and hand-actuated means for shifting it in a reverse direction.

5 4. A cutting-machine for the purposes described, comprising in combination a supporting-table, a cutting mechanism which includes a fixedly-held bottom knife and an upper knife hinged to the lower knife at one end and normally held to its open position, a means for raising the two knives in unison with respect to the table-top, and a trip device for releasing said means from engagement with the cutting mechanism as set forth.

15 5. The combination with the table the $\square$ -shaped frame disposed transversely thereof and having its pendent members formed with rack-faces, said $\square$ -shaped members having vertical movement on the table-frame, a bot-

tom knife fixedly secured to the cross-bar of the $\square$ -shaped frame, an upper knife hinged to the said cross-bar, the frame H horizontally mounted under the table and having endwise movement, the shaft mounted in the front end of the frame H having pinions for engaging the rack portions of the $\square$ -shaped frame, a ratchet fixedly mounted on the shaft, a pawl-carrying lever loosely mounted on the shaft, a foot-actuating device for the pawl-lever, and a hand-lever mechanism for shifting the frame to disengage the pinions on the shaft from the rack portions of the $\square$ -shaped frame as set forth.
